UNITED STATES PATENT OFFICE.

OMAR J. HOTALING, OF EAST ORANGE, NEW JERSEY.

VENDING MACHINE.

1,414,085.

Specification of Letters Patent. Patented Apr. 25, 1922.

Application filed November 4, 1920. Serial No. 421,662.

To all whom it may concern:

Be it known that I, OMAR J. HOTALING, a citizen of the United States, and a resident of East Orange, in the county of Essex and State of New Jersey, have invented a new and Improved Vending Machine, of which the following is a full, clear, and exact description.

This invention relates to a vending machine and has particular reference to an improvement in a delivery mechanism therefore.

One of the principal objects of the invention is to provide an extremely simple and inexpensive delivery mechanism for vending machines which comprises relatively few working parts which are assembled and related in such a manner as to positively feed by gravity the articles to be dispensed.

Another object of the invention resides in the provision of a delivery mechanism, normally locked against operation and coin or check actuated mechanism for releasing the same to permit of operation of the delivery mechanism.

The invention further contemplates the provision of a delivery mechanism for non-circular, identically-shaped articles, in combination with means for maintaining a stack of said articles against relative rotation with the greatest dimension of each article out of alignment with respect to the next adjacent article whereby the lowermost articles will support the remainder of the stack until relative rotation between the delivery mechanism and the stack has been effected.

A further object in view is to provide a stack supporting and releasing member provided with a non-circular delivery opening of identical formation to the articles of the stack, whereby upon relative rotation of said stack supporting and releasing member and the stack, the lowermost article of the stack will be released, to singly and successively deliver the same.

A still further object of the invention is to provide an operating means for effecting relative rotation of the stack supporting and releasing member and the stack and a locking device for said operating means together with a coin actuated mechanism for releasing said locking device.

Due to the fact that the lock releasing mechanism must necessarily allow for an initial movement to permit the coin or check

to effect a release of the same, it has been found necessary to provide a means for returning the mechanism to normal position and it is therefore a further object of the invention to provide means for accomplishing said return movement.

With the above recited and other objects and advantages in view which will appear from the following detailed description, reference is had to the accompanying drawing forming a part of this application, wherein:

Figure 1 is a front elevation of a vending machine constructed in accordance with the invention.

Figure 2 is a vertical transverse sectional view therethrough.

Figure 3 is a horizontal sectional view therethrough taken approximately on the line 3—3 of Figure 2.

Figure 4 is a similar view taken on the line 4—4 of Figure 2.

Figure 5 is a detail front elevation of a portion of the operating and locking means for the delivery mechanism, and the coin actuated releasing means therefor, parts being broken away to disclose the underlying structure.

Figure 6 is a sectional view taken on the line 6—6 of Figure 5.

Figure 7 is a view similar to Figure 5 illustrating the position of parts when the same have been operated to release the locking means.

Figure 8 is a rear elevation of the parts illustrated in Figure 5.

Referring to the drawings by characters of reference which denote like parts throughout the several views thereof, 10 designates a cabinet divided horizontally to provide an upper receptacle 11 for the articles to be dispensed and a lower compartment 12 in which is arranged a delivery slide 13 which functions to gravitationally receive and deliver the articles through a delivery opening 14 in the front wall of said compartment. The machine is designed for vending non-circular articles of identical shape such as illustrated in the drawings by the character 15 and the delivery mechanism of the machine depends for its operation on articles of this shape. The term non-circular is employed in its broadest sense to convey the meaning that the articles of whatsoever shape may be dispensed by

machine which have a major dimension greater than the other or others. To accomplish the purpose of the invention the packages are arranged in stacked relation with 5 the greatest dimension of each disposed out of alignment with the next adjacent article. By way of illustration the articles are shown as oblong and in this instance, to maintain the same against relative movement with respect to each other when so stacked, the receptacle is provided with a partition 16, having stepped depressions 17 and 18, which accommodate respectively, the end of each alternate article and the side of the remaining articles. In order to gain access to the 10 interior of the receptacle an opening adapted to receive a removable front panel 19 is provided. The panel has secured to the inner face the brackets 20 which support the vertical guide bars 21, arranged in such a manner when closed, as to function and 15 contact with the depressions 17 and 18 to maintain an alternate arrangement of the packages 15 in the stack, against relative movement. The front of the lower compartment 25 20 is closed by door 22 hinged as at 23, and the upper edge of said door is provided with rearwardly projecting, apertured lugs 24 designed to receive studs 25 depending from the lower end of the panel when the same is 25 positioned to close the receptacle 11. A suitable key actuated lock 26 serves to secure the panel in closed position and further functions, through the medium of the engagement of the studs 25 with the apertured 30 lugs 24, to obstruct the opening of the door until the panel has been unlocked and removed.

The delivery mechanism or means for successively releasing the lowermost packages 40 from the stack, comprises a rotary disc 27, disposed horizontally within the cabinet immediately below the receptacle 11. The periphery of the disc is provided with a depending annular rack 28 and the disc is mounted for rotation on the annular flange 29, supported from the walls of the cabinet. The disc is provided with a centrally arranged oblong opening 30 which is of a corresponding 45 shape and appropriate size to permit of the passage of the packages 15 therethrough, when the major dimension of said opening and package coincide. Normally the lowermost package supports the stack until the disc is rotated, due to the fact that the major dimension of the disc and the opening are out of alignment. When the disc is rotated, it will be apparent that the opening 30 will coincide and register with 50 the lowermost package to permit the same to drop therethrough by gravity. It will be further apparent that each corresponding movement of the disc will serve to release the packages successively, until the stack is depleted.

The mechanism for operating the disc comprises an operating shaft 31, journaled in the door 22 and provided with an exteriorly arranged operating crank handle 32. Keyed to the inner end of the operating shaft 70 is a pinion 33, the teeth of which mesh with the annular rack 28 to transmit motion from the operating shaft to the disc. The ratio of the pinion 33 to the rack 28 is here illustrated as four to one whereby a quarter revolution of the rack is effected upon each revolution of the pinion. A ratchet mechanism including ratchet wheel 34 keyed to the operating shaft 31, and ratchet pawl 35 mounted on the door 22, functions to limit the rotation of the operating shaft in an anti-clockwise direction. The means for locking the operating handle and shaft against free rotation in a clockwise direction, comprises a barrel 36 keyed to the operating shaft, and 75 provided with an annular groove 37 to freely receive the nose 38 of a locking pawl 39 mounted on a stud 40 projecting from the inner surface of the door 22. A locking notch 41 is formed in the bottom wall of the groove to engage the nose 38 of the pawl for locking the barrel after each revolution. The locking pawl is provided with a transversely projecting trunnion 42 and the barrel is provided with a radial coin receiving depression 43 at one side of the locking notch and in parallel relation to the groove 37, whereby upon the reception of the proper coin or check, an initial rotation of the drum 80 will effect the engagement of the periphery of the coin with the trunnion 42, to lift the nose 38 of the pawl out of engagement with the locking notch 41. The door is provided with an upstanding coin guide 44 having a coin receiving opening 45 in its front face, which communicates with the coin slot 46 therein, whereby upon the insertion of a coin, the same will be guided to properly 85 gravitate into the coin receiving depression 43. As it is essential to permit of an initial free rotary movement of the operating shaft to allow the coin to engage the trunnion for releasing the nose 38 of the locking pawl from the locking notch, it is necessary to construct the ratchet wheel 34 to admit of a slight retrograde movement of the drum by eliminating one of the ratchet teeth as clearly illustrated in Figures 7 and 8 of the drawings. It is therefore deemed expedient to provide means for returning the drum to a 90 position to normally dispose the coin receiving depression beneath the coin slot and to this end a return arm 47 is provided which is journaled on the stud 40. A tension spring 48 connects the return arm 47 and locking pawl 40 for the dual purpose of retaining the nose of the pawl 40 in engagement with the bottom wall of the groove and throwing the return arm in the proper direction to cause the heel 49 thereof to engage 95

with the wall 50 of the notch 51 whereby the drum will be rotated anti-clockwise, until the ratchet means functions to prevent further rotation in such a direction.

- 5 In use of the machine, the stack of alternately arranged articles or packages 15 is placed in the receptacle 11, with the major dimension of the lowermost package disposed out of alignment with the major 10 dimension of the oblong opening 30. To operate the machine, a coin or check is inserted in the opening 45 and will gravitate through the coin slot 46 into the coin receiving depression 43 of the barrel. The operating handle 32 is then rotated clock-wise or in the direction indicated by the arrow on Figure 1 of the drawings. The initial rotation of the crank handle operating shaft and barrel 36 will effect the engagement of 15 the periphery of the coin with the trunnion 42 to lift the nose 38 of the locking pawl 39 whereby the locking notch 41 may pass beyond the nose of the pawl. Further rotation of the drum will disengage the coin 20 from the trunnion 42 and permit the nose 38 of the pawl to be drawn into engagement with the bottom of the groove 37 under the action of the tension spring 48 whereby the nose of the pawl will be in a position to be 25 drawn by said spring into the locking notch 41 when a complete revolution of the drum has been made. As the drum and operating shaft revolve, pinion 33 which is also keyed to the operating shaft turns therewith and 30 due to the engagement of its teeth with the annular rack on the disc 27, said disc will be rotated thereby. As illustrated the ratio of the pinion 33 and the rack 28 is four to one, therefore a complete revolution of the 35 operating crank arm will rotate the disc 27 one quarter of a revolution, which will bring the major axis of the opening 30 in the disc into registry with the major axis of the lowermost article or package 15 of the stack. 40 This will permit said lowermost package to fall through the opening and gravitate down the delivery slide 13 thence through the delivery opening 14. When the coin receiving depression during the rotation of the barrel, 45 reaches a point immediately above the coin receptacle 52 on the front wall of the lower compartment, the coin will gravitate therefrom into said receptacle. The ratchet wheel 34 and pawl 35 function in the usual 50 manner to prevent retrograde movement of the shaft, barrel and pinion, but as heretofore described one tooth is preferably omitted in order that a slight retrograde movement may be had, should the drum upon 55 completion of one revolution advance thereby beyond to a point where the nose 38 of the locking pawl engages the end of the locking slot 41. By the omission of this tooth provision is made to permit the tension spring 60 48 to automatically rotate the drum anti- 65 clockwise until the ratchet pawl engages the next tooth. This slight retrograde movement is accomplished by the engagement of the heel 49 of the return arm with the end 50 of the slot 51 as the return arm is swung 70 upward under the action of the tension spring 48. When it is desired to refill the receptacle and collect coins deposited in the coin receptacle, the removable panel is unlocked and removed thereby uncovering the 75 opening in the cabinet and permitting the door 22 to be swung open upon its hinges.

This machine may be varied to accommodate articles of various shapes which have one dimension greater than the other or 80 others and will operate equally as well on square, oval, polygonal, hexagonal or other articles falling under the general term of a non-circular shape, the only limitation necessary is that the shape of the opening and 85 the supporting and releasing disc must correspond to the shape of the articles to be vended from the machine.

While there has been illustrated and described a single and preferred embodiment 90 of the invention, it is to be understood that the right is reserved to various other forms than those actually illustrated, to the full extent of the general meaning in which the terms of the claims are expressed, or by 95 variations in the phrasing of the same.

Having thus described my invention, I claim as new and desire to secure by Letters Patent:—

1. In a vending machine for non-circular 100 articles, the combination with means for maintaining the articles in cross stacked relation and a stack supporting and delivery member, of a coin controlled mechanism for effecting relative rotation between the stack 105 and said member to release and deliver the lowermost article, comprising an annular rack on said member, a crank shaft, a pinion secured thereto and meshing with the rack, means for preventing rotation of the 110 crank shaft in one direction, a drum secured to the crank shaft, a locking notch in said drum, a pawl pivotally mounted adjacent said drum and adapted to normally engage said notch for preventing rotation of the shaft in the other direction, a coin receiving slot in the drum, and a trunnion on the pawl disposed in the path of movement of the coin and adapted to coact with the coin to release the pawl from the locking notch to permit of free rotation of the 115 crank shaft.

2. In a vending machine, the combination of a rotary apertured delivery disk and superposed means adapted to support and maintain a plurality of articles to be vended in cross stacked relation, of coin controlled mechanism for rotating said disk comprising an annular rack on said disk, a crank shaft, a pinion secured thereto and mesh- 120 125 130

ing with the rack, means for preventing rotation of the crank shaft in one direction, a drum secured to the crank shaft, a locking notch in said drum, a pawl pivotally mounted adjacent said drum and adapted to normally engage said notch for preventing rotation of the shaft in the other direction, a coin receiving slot in the drum, and a trunnion on the pawl disposed in the path of movement of the coin and adapted to coact with the coin to release the pawl from the locking notch to permit of free rotation of the crank shaft.

3. In a vending machine, the combination of a rotary apertured delivery disk and superposed means adapted to support and maintain a plurality of articles to be vended in cross stacked relation, of coin controlled mechanism for rotating said disk comprising a rotary actuating shaft having operative connection with the disk for rotating the same therewith, means for preventing rotation of said shaft in one direction, means

for normally locking the same against rotation in the opposite direction, a member mounted on said shaft having a coin receiving notch adapted to engage the locking means for releasing the same upon initial movement of the actuating shaft.

4. A vending machine for oblong articles comprising a cabinet having a lower delivery compartment and a superposed receiving compartment, a rotary delivery member separating the same and provided with an oblong delivery opening therethrough to admit of the passage of the articles therethrough when the major axis of the articles and the opening coincide, means in the receiving compartment for maintaining the articles in cross stacked relation, means for preventing rotation of the delivery member in one direction, means for locking said member against rotation in the opposite direction, and coin operated means for actuating the releasing means.

OMAR J. HOTALING.
